UNITED STATES PATENT OFFICE.

KARL C. SCHMIDT AND HENRY G. LYKKEN, OF GRAND FORKS, NORTH DAKOTA.

CLAMP FOR SURVEYORS' BAND-CHAINS.

1,307,707.

Specification of Letters Patent. Patented June 24, 1919.

Application filed March 12, 1917. Serial No. 154,420.

To all whom it may concern:

Be it known that we, KARL C. SCHMIDT and HENRY G. LYKKEN, citizens of the United States, residing at Grand Forks, in 5 the county of Grand Forks and State of North Dakota, have invented a new and useful Clamp for Surveyors' Band-Chains, of which the following is a specification.

This invention has reference to clamps for 10 surveyors' band chains, and its object is to provide a simple and efficient device for holding a band chain in compact form with the chain readily removable from the clamp, and avoiding the disadvantages incident to 15 the use of a reel for carrying the chain.

In accordance with the present invention there is provided a series of leaves or plates with a carrier for holding the plates in face to face relation, but yieldably, with each 20 plate having a recess or socket to receive a corresponding portion of the band chain, while the plates have lips with mouth portions leading to the sockets to readily direct the band chain thereto.

25 Band chains are sometimes wound upon reels, but this arrangement has the disadvantage that the chains frequently bind and stick on the reel because no opportunity is given to clean or dry the chain when used in 30 wet weather as the chain is tightly coiled on the reel. Moreover, a reel, on account of its size, is inconvenient to carry.

It is quite common for surveyors to fold the chain back and forth upon itself with 35 the loops extending on opposite sides of a central portion, and then to tie the band chain or tape at the central portion by means of a string or wire. This, however, is inconvenient since it provides no means for releasing less than the full length of the band chain.

The invention has the advantage of not only providing for the looping and securing of the chain, but presents a small and compact device which may be readily carried in 45 a small pocket, and a device in which the chain will not stick or bind, while the chain is exposed in most part for drying and cleansing when needed. Furthermore, any portion of the chain may be released and 50 used, while the unused portion remains secure, and both the operations of securing and releasing are easily and speedily performed.

The invention provides a holding device 55 in which the chain may be looped in such manner that each loop shall contain a deter-

minate amount of chain, say, five feet, more or less. It furthermore permits the display of the index figures on the same side of the tape or chain as the successive loops are 60 formed, this being accomplished by giving each loop a half twist on itself. Thus, when the chain is all looped it may be "thrown" in a manner familiar to surveyors, and forms 65 a compact bundle approximately ten inches in diameter.

The invention will be best understood from a consideration of the following detailed description, taken in connection with the accompanying drawings forming part of this 70 specification, with the further understanding that while the drawings show a practical form of the invention, the latter is not confined to any strict conformity with the showing of the drawings, but may be changed 75 and modified so long as such changes and modifications come within the scope of the appended claims.

In the drawings:

Figure 1 is a longitudinal diametric section 80 of one form of the invention.

Fig. 2 is a side elevation, with some parts in section, of another form of the invention.

Fig. 3 is a longitudinal section with some parts in elevation of still another form of 85 the invention.

Fig. 4 is a section on the line 4-4 of Fig. 1.

Fig. 5 is a section on the line 5-5 of 90 Fig. 2.

Fig. 6 is a section on the line 6-6 of Fig. 3.

Figs. 7, 8 and 9 are perspective views of different forms of plates or leaves used in the several forms of holders shown in Figs. 95 1, 2 and 3.

Fig. 10 is a perspective view showing a step in the operation of contracting the sides of a bundle of loops of the surveyor's band chain to make a more compact bundle. 100

Fig. 11 is a perspective view illustrating another step, whereby the already contracted bundle of loops may be still further contracted in size.

Fig. 12 is a perspective view, more or less 105 in diagram and exaggerated, showing the completion of the step illustrated in Fig. 11 but confined to a series of single loops.

Referring, first, to the form of the invention illustrated in Figs. 1, 4 and 7, there is 110 shown a casing 1 of approximately cylindrical form having a cut-away portion indi-

cated at 2 and extending for the greater portion of the length of the casing. The cylindrical casing 1 is provided with plug caps or heads 3, 4, respectively, forming closures for 5 the ends of the casing. There is also provided a series or stack of plates 5, one of which is shown separately in Fig. 7. Each plate has a disk end 6 to fit the cylinder 1, the disk having a central opening 7 contributing 10 to the lightness of the structure. Projecting radially from each plate 5 is a tongue 8, which in the particular showing of the drawings has parallel sides, and is of a length to project through the cut-away portion 2 of 15 the casing and for a distance beyond the latter. Each tongue 8 terminates in a beveled portion 9, and adjacent to the disk 6 is provided with a recess or pocket 10 extending crosswise of the tongue, and substantially 20 tangential to the disk 6.

In addition to the plates 5 there are two other plates 5^a, constituting a top plate, and 5^b, constituting a bottom plate of the assembled series, the other plates being all 25 alike. The plate 5^a differs from the plates 5 in that it has no recess or pocket 10. The plate 5^b differs from the plates 5 in that it has no beveled extremity 9. Otherwise the plates are all alike. 30 The plates 5 are stacked within the casing 1 from the head 4 toward, but stopping short of the head 3, and between the head 3 and the topmost plate 5^a there is lodged a spring 11.

35 The structure of Fig. 2 differs somewhat from that of Fig. 1. There is provided in the structure of Fig. 2 a flat post 12 having a head 13 at one end and traversed by a pin 14 near the other end. There is provided a series of plates or leaves 15 of generally rectangular form, each having a passage 16 therethrough, so that the plates may be threaded upon the post 13 in superposed order. The passage 16 is placed near one 40 end of the plate, so that the other end of the plate constitutes a projecting tongue 17 corresponding to the tongue 8 of the plates 5. Each tongue 17 terminates in a beveled extremity 18 like the beveled end 9 of the 45 plates 5, and each tongue 17 has a transverse recess or pocket 20 extending clear across it and corresponding to the recess or pocket 10 of the plates 5. There are also provided other plates 15^a and 15^b differing from the 50 plates 15 in the same respects as the plates 5^a and 5^b differ from the plates 5.

The structure of Fig. 3 differs from the structure of Figs. 1 and 2 in that there is provided a casing 21 of approximately semi-cylindrical or segmental form, and of a diameter sufficient to accommodate a stack of leaves or plates 22 similar to but differing somewhat from the plates 15. Each plate 22 has at a point intermediate of its ends 55 oppositely disposed recesses 23 entering the

opposite edges of the plate and dividing the body of the plate from a tongue extension 24 having a beveled extremity 25 and a transverse recess or pocket 26 between the extremity 25 and the recesses 23. The stack 70 of plates 22 has a top plate 22^a and a bottom plate 22^b differing from the plates 22 in the same respects as the similarly disposed plates of the structures shown in Figs. 1 and 2.

75 The casing 21 is provided with diametric inwardly directed flanges 27 entering the recesses 23 and other flanges 28 similar to the flanges 27 and arranged above the top plate 22^a and below the bottom plate 22^b of 80 the stack of plates in the casing 21. A leaf spring 29 is inclosed in the casing 21 with its extremities bearing against the plates 22^a and 22^b and extending beyond the flanges 28 and serving to hold the stack of plates 22 85 in elastically yieldable face to face relation.

In order to permit the assembling of the structure of Fig. 3, one side 21^a of the casing 21 may be formed separately and after 90 the assemblage of the parts is united to the casing by soldering, or by screws, or in any other suitable manner.

95 All the different forms of the invention operate in the same manner, so that a description of one form applies to all the forms and to still other forms which the invention may assume, but which have not been shown in the drawings.

One end of a tape-like surveyor's band 100 chain which consists of a relatively narrow and thin steel band of suitable length has one end inserted between one end plate and the next in order, the insertion being in a direction edgewise of the band until the band seats in a pocket 10 or 20 or 26, as the 105 case may be, the remaining plate or plates of the stack yielding for the purpose. As soon as the band is seated in a pocket, it becomes temporarily locked therein by the return of the displaced plate or plates under 110 the action of the spring urging the plates together. The band is then formed into a loop and inserted between the next two plates in order and carried to the other side of the stack of plates, where it is again 115 formed into a loop and brought back to the stack of plates and there inserted and seated in a corresponding pocket, and so on, until the entire chain folded back and forth upon itself is confined midway of the folded portions by the holding device or clamp. The 120 arrangement permits of the loops being of determinate lengths, say, five feet each, more or less, with the index figures all on the same side of the tape so as to be readily observable. The loops are all open so as to be readily accessible for cleansing and observation, wherefore any desired length of the band chain may be removed from the clamp, and there is no liability of sticking or binding 125 130

while the band may be readily cleansed at any time, even though contained in the clamp.

The carrying means for the series of 5 plates, or, in the case of the structure of Fig. 2, that portion of the series of plates held together by the carrying means, constitutes a convenient hand hold for grasping the structure while the band chain is being inserted or removed and may be utilized for the attachment of other carrying means facilitating the transportation of the coiled chain.

While the invention has been described as 15 providing a holding means or clamp for a surveyor's band chain, it is not necessarily confined to such particular use, but may be used for other purposes for which it may be adapted. The pockets or receptacles formed 20 by the recesses 10, 20 or 26, each with the next plate in order constituting a cover and holding member therefor, may be shaped in accordance with the article or articles to be lodged and held therein.

25 In Fig. 3 there is shown a strap 30 having one end 31 secured to the casing 21 adjacent to one end of the stack of plates 22. The strap is passed through an eye 32 near the other end of the stack of plates and secured 30 to the casing 21, and then returned upon itself and made fast by a buckle 33 to the first-mentioned portion of the strap near the end 31. This provides for securing secondary bundles of loops after throwing the 35 tape, and is particularly useful when handling extra long tapes, say, tapes of two or three hundred feet in length, where the clamp structure is of a size intended primarily for a hundred foot tape. The strap 40 represents one of the simplest means for the purpose, but other means may be employed. In Fig. 10 a long surveyor's band chain 34, say two or more hundred feet in length, is shown applied to the clamp to constitute a 45 bundle 35 of loops of large diameter. This bundle of loops is shown as being twisted into figure-of-8 form with an intermediate portion 36 to be ultimately brought to the clamp so as to engage between said clamp 50 and the inner or first loop of the strap 30. In Fig. 11, the intermediate portion 36 is shown as already secured by the strap 30 passed through the eye 32, thus forming another coil 35^a of double the thickness of 55 the coil 35. This coil is again twisted, as in Fig. 10, and its intermediate portion 36^a, after the bundle 35^a is twisted, as in Fig. 10, is brought to the clamp outside of that part of the strap 30 holding the intermediate portion 36, and the remainder of the strap is used to secure the whole bundle of loops to the clamp, the strap being passed through 60 and secured in the buckle 33.

In Fig. 12 the arrangement of the series 65 of loops is diagrammatically represented

for the purpose of simplicity and the parts are somewhat exaggerated to permit such showing.

It will be understood that the clamp may be used without the strap if so desired, and 70 is usually so used where the chain is of relatively short length. The manner of holding a long band in the clamp by the aid of the strap is advantageous in permitting compactness of assemblage.

75 The recesses or pockets in the plates designed to receive the tape may have the entering side walls slightly beveled, as indicated, to facilitate the removal of the tape when desired.

80 What I claim is:—

1. A clamp for surveyors' band chains, comprising a series of plates or leaves and means for holding them in elastically yieldable face to face relation, the leaves being 85 provided with recesses or pockets for the reception of corresponding portions of the band chain.

2. A clamp for surveyors' band chains, comprising a series of leaves or plates in face 90 to face relation with the leaves having projecting portions or tongues provided with transverse recesses or pockets for receiving corresponding portions of a band chain, and a holder for the leaves engaging those parts 95 of the leaves remote from the tongues and having a spring for yieldably confining the leaves in face to face relation.

3. A clamp for holding a surveyor's band chain, comprising a series of plates or leaves 100 each having a tongue projection with a beveled extremity and a transverse recess or pocket adjacent to the extremity, and holding means engaging the leaves at those portions remote from the beveled extremities 105 and including spring means for holding the plates in yieldable face to face engagement.

4. A clamp for holding a surveyor's band chain, comprising a series of plates or leaves 110 each having a tongue projection with a beveled extremity and a transverse recess or pocket adjacent to the extremity, and holding means engaging the leaves at those portions remote from the beveled extremities 115 and including spring means for holding the plates in yieldable face to face engagement, the series of leaves being provided with end leaves one of which lacks the bevel at the extremity and the other of which lacks the transverse recess or pocket.

120 5. A clamp for holding a surveyor's band chain, comprising a casing, a series of plates or leaves in face to face engagement with one end of each leaf lodged in the casing and the other end of each leaf in the form of a tongue projecting from the casing and there provided with a transverse recess constituting a pocket, and with the extremities shaped to guide the band into the pockets, and a spring in the casing holding the series 125 130

- of leaves in elastically yieldable face to face engagement.
6. A clamp structure comprising a series of leaves or plates and means for holding them in elastically yieldable face to face engagement, the plates of the series each having a receiving portion for retaining an article lodged therein.
7. A clamp structure comprising a series of leaves or plates and means for holding them in elastically yieldable face to face engagement, the plates of the series each having a receiving portion for retaining an article lodged therein, and the plates adjacent to the receiving portions being shaped to guide the article thereto.
8. A holding structure, comprising a series of leaves or plates with receptacles therein and carrying means for the plates holding the latter in elastically yieldable face to face relation.
9. A clamp for surveyors' band chains, comprising a series of plates or leaves and means for holding them in elastically yieldable face to face relation with the leaves provided with recesses or pockets for the reception of corresponding portions of the band chain, the wall of each recess where the band enters and leaves being beveled to facilitate the removal of the band from the pocket.
10. A clamp for surveyors' band chains provided with devices for holding corresponding portions of the band chains in loops or coils, a loop at one end of the clamp, a buckle at the other end of the clamp, and a strap fast to the end of the clamp carrying the buckle and capable of being threaded through the loop and secured in the buckle.
11. A clamp for holding a surveyor's band chain, comprising a casing, a series of leaves or plates mounted in the casing in the form of a stack in face to face relation, with each leaf having a tongue projection with a beveled extremity, and pockets back of said beveled extremity and exterior to the casing, and a spring in the casing for holding the plates in face to face contact.
12. A clamp for holding a surveyor's band chain, comprising a casing, a series of leaves or plates mounted in the casing in the form of a stack in face to face relation with each leaf having a tongue projection with a beveled extremity, and pockets back of said beveled extremity and exterior to the casing, and a spring in the casing for holding the plates in face to face contact, the casing and plates having coacting portions for preventing escape of the plates from the casing.
13. A clamp for holding a surveyor's band chain, comprising a casing open along one side, a stack of plates each in part lodged within the casing and in part exterior thereto, with the exterior portion provided with recesses constituting pockets for holding corresponding portions of the band, and a spring in the casing for holding the plates yieldably in face to face condition.
14. A clamp for holding a surveyor's band chain, comprising a cylindrical casing open at one side lengthwise of the casing, heads for closing the ends of the casing, a stack of plates in the casing each of a shape to fit within the casing and each having a tongue extension projecting through the open side of the casing and provided with a recess or pocket for receiving a corresponding portion of the band, and a spring within the casing engaging the stack for holding the plates yieldably in face to face relation.

In testimony that we claim the foregoing as our own, we have hereto affixed our signatures in the presence of two witnesses.
